CROSS RIDGE AND BRACE CONSTRUCTION
FOR FREIGHT CARS

Wendel J. Meyer, Philadelphia, and Thomas W. Demarest, Haverford, Pa., assignors to The Pennsylvania Railroad Company, Philadelphia, Pa., a corporation of Pennsylvania

Application October 20, 1937, Serial No. 169,980

13 Claims. (Cl. 105—249)

This invention relates to cross ridge and brace construction for freight cars, particularly freight cars of the open hopper type such as are ordinarily used in the transportation of coal, gravel, sand and other granular or comminuted materials.

One object of our invention is to make it possible to effectively support and brace the side walls of a car of the kind referred to interiorly with imposition of a minimum of obstruction to the ready introduction and withdrawal of a crane operated clam bucket in loading or unloading the car and to the free horizontal flow and distribution of the materials which are to be carried, throughout the length and breadth of the car.

Another object of our invention is to secure the above advantages with a simple cross ridge construction with side wall buttressing braces so arranged that the stresses are communicated directly to the cross bearer or bearers of the car, and secured to said cross bearer or bearers in such manner as to be easily removable and replaceable when necessary by reason of being damaged or corroded.

Other objects and attendant advantages will appear from the following detailed description of the attached drawings; wherein Fig. I is a fragmentary view in transverse section of an open top hopper car embodying our improved cross ridge and brace construction, the section being taken as indicated by the arrows I—I in Fig. II.

Fig. II is a fragmentary detail plan section view taken as indicated by the arrows II—II in Fig. I.

Fig. III is a fragmentary view of the car in longitudinal section taken as indicated by the arrows III—III in Fig. I.

Figs. IV and V are fragmentary detail sections taken as indicated respectively by the arrows IV—IV and V—V in Figs. I and IV.

Figs. VI and VII are views like Figs. I and II showing a modified embodiment of our invention.

With reference first more particularly to Figs. I—V of these illustrations, the center sill of the car is comprehensively designated by the numeral 1, and shown as being formed by two opposingly-arranged Z-bars 2, 2; while one of the side sills is indicated at 3, and one of the side wall sheet-supporting stakes at 4. Jointly with others (not shown) arranged at intervals along the length of the car, the stake 4 supports the side sheet 5 and is connected with the others at its upper end by a top rail 6—all after more or less usual practice in the art. It is, of course to be understood that

the same construction obtains at the other side of the car.

The cross ridge construction with which the present invention is more especially concerned comprises a cross bearer 7 which extends transversely of the center sill 1, and to the ends of which the side sills 3 are secured. As shown the cross bearer 7 is of composite or built up formation, with complementary vertical web side components 8 which are flanged at their inner ends 9 and at 9 respectively secured by said flanges to the Z-bars 2 of the center sill 1, and with a top or compression chord in the form of a flanged member 10 which is attached to the upper edges of said side components and which bridges the center sill 1. The web components 8 of the cross bearer are provided at their outer ends with flanges 11 for convenience of attaching the corresponding side sills 3, and at their lower edges with flanges 12 for attachment of a bottom tension chord plate 13 which extends beneath the bottom flanges of the center sill bars 2, from one side sill 3 to the other. For the sake of added strength and rigidity, upper and lower filler pieces 15 and 16 (Fig. I) are preferably employed to unite the cross bearer 7 to the sill 1. The upper filler piece 15 is in the form of an angle bracket with its vertical flange riveted to the flange member 10 in the interval between the inner sides of the web components 8 of the cross bearer 7 and its horizontal flanges riveted to the top flanges of the center sill bars 2. The lower filler piece 16, on the other hand, is riveted to the plate 13 and acts as a spacer between the bars 2 at the bottom of the center sill 1, it being provided with upstanding end flanges 17 which are riveted to the vertical webs of said center sill bars 2. As shown, the plate 13 is also riveted directly to the bottom flanges of the center sill bars 2. Preferably also, angle plates 18 (Figs. I, IV and V) are employed to strengthen the connections between the outer ends of the cross bearer web components 8 and the side sills 3.

A centrally-peaked ridge sheet shown at 19 and forming a portion of the bottom of the car between the openings for the doors whereof one is shown at 30 in Fig. IV, arches the juncture between the center sill 1 and the cross bearer 7 and rests throughout its width directly upon the top flange member or compression chord 10 of said cross bearer. In the illustrated instance, the side edges of the ridge sheet 19 are turned up as at 21 in Figs. I and III and riveted fast to the side wall sheets 5 of the car. However, if desired or found convenient in practice, the side edge of the

ridge sheet 19 may be butt-welded directly to the side sheets 5. From Fig. II it will be observed that, immediately beyond the opposite sides of the cross bearer 1, the ridge sheet 19 is cut away as at 22, 22 to clear the center sill 1, the gaps thus formed being bridged by upwardly rounded longitudinal hood sheaths 23.

For the purpose of buttressing the side walls 5 of the car at the stakes 4, we have provided brace 10 means including a pair of complementarily-inclined bars 25, which, at their lower ends, are secured to a connection plate 26 extending up through the ridge sheet from the cross bearer. As shown, the connection plate 26 lies crosswise 15 of the center sill 1 and is secured along its bottom edge to the cross bearer web components 8 and to the compression chord 10, as well as to the upper filler piece 15. At their upper ends, the brace bars 25 are secured, with interposition of angle brackets 27 to the side wall stakes 4. Welding is resorted to, as conventionally indicated by 28, to seal up the slit opening where the connection plate 26 passes through the ridge sheet 19.

As a result of the construction just described, it will be apparent that when necessary due to being damaged or badly corroded, the brace bars 25 can be easily and quickly removed and replaced at relatively small expense without entailing disassembling any parts of the cross bearer.

As an alternative, the brace bars 25 may be formed as a unit, with an integral juncture between them at the region of their convergence, instead of separately as above described.

In the modified form of our invention illustrated in Figs. VI and VII, the side wall buttressing means consists simply of a pair of brace bars 25a, which extend downward through the ridge sheet 19 and are directly secured at their bottom ends to the respective web components 8, 8 of the cross bearer 1. Otherwise the construction in Figs. VI and VII is exactly like that of the first described embodiment. Accordingly, in order to preclude repetitive description, all corresponding parts have been identified with the same reference numerals previously employed.

From the foregoing, it will be apparent that we have provided a simple cross ridge and brace construction for open freight cars, which is light though sturdy, and in which the cross bearer is wholly below and directly supports the ridge sheet 19 which forms a part of the bottom of the car. As a consequence, in the form of our invention shown in Figs. I-V, the interior of the car is clear of obstruction, except for the narrow anchorage plate and the narrow brace bars 25, so that maximum clearances are provided for ready manipulation of a clam bucket in loading or unloading, as well as for free horizontal flow of the granular or comminuted material which is to be carried, both longitudinally and laterally of the car. In the form of our invention shown in Figs. VI-VII, such flow of material is even less restricted due to the absence of the connection plate used in the bracing means of the first embodiment.

Having thus described our invention, we claim:

1. Cross ridge and brace construction for hopper cars and the like, comprising a cross bearer which extends from side to side of the car; a continuous ridge sheet overlying the cross bearer; and side wall brace means extending through an opening in the ridge sheet and connected to the cross bearer.

2. Cross ridge and brace construction for hop-

per cars and the like according to claim 1, wherein the ridge sheet has a rounded peak where it overlies the cross bearer.

3. Cross ridge and brace construction for hopper cars and the like, comprising a cross bearer 5 which extends from side to side of the car; a continuous ridge sheet with a rounded peak overlying the cross bearer; a connection plate secured to the cross bearer and extending through an opening in the ridge sheet; and side wall 10 braces secured to the connection plate.

4. Cross ridge and brace construction for hopper cars and the like, according to claim 3, wherein the connection plate extends up through the ridge sheet, and wherein the side wall braces 15 are secured to the connection plate above the ridge sheet.

5. Cross ridge and brace construction for hopper cars and the like, comprising a cross bearer which extends from side to side of the car, with 20 a vertical web and top and bottom flanges; a continuous ridge sheet with a rounded peak overlying the cross bearer; a connection plate directly attached to the cross bearer and extending up through an opening in the ridge sheet; and 25 side wall braces secured to the connection plate above the ridge sheet.

6. Cross ridge and brace construction for hopper cars and the like with a center sill, comprising a cross bearer with a vertical web and top 30 and bottom flanges extending from one side to the other of the car; a continuous ridge sheet with a rounded peak overlying the cross bearer and connected to the top flange of the latter; a connection plate secured to the center sill and 35 the cross bearer and extending up through an opening in the ridge sheet; and side wall braces secured to the connection plate above the ridge sheet.

7. Cross ridge and brace construction for a 40 hopper car or the like with a center sill and side sills, comprising a cross bearer which extends transversely of the center sill and to the ends of which the side sills are secured, a continuous ridge sheet overlying the center sill and having 45 a rounded peak over the cross bearer, and transverse side wall brace means extending down through an opening in the ridge sheet for attachment to the cross bearer in the region of the center sill embodying complementarily-inclined upwardly and outwardly-reaching brace bars, which, at their upper ends are secured to the corresponding side walls at a level above that of said cross bearer.

8. Cross ridge and brace construction for a 55 hopper car or the like with a center sill and side sills, comprising a cross bearer which extends transversely of the center sill and to the ends of which the side sills are secured, a continuous ridge sheet overlying the center sill and having 60 a rounded peak over the cross bearer, and transverse brace means including a pair of complementarily-inclined brace bars respectively secured at their upper ends to corresponding side wall stakes, and a connection plate to which said 65 brace bars are secured at their lower ends, said connection plate extending down through an opening in the ridge sheet crosswise of the center sill and being secured to the cross bearer.

9. Cross ridge and brace construction for a 70 hopper car or the like, according to claim 6, wherein the cross bearer is of composite construction with complemental vertical web side components secured at their inner ends to opposite sides of the center sill, and with a ridge

sheet supporting flange bar secured along the upper edges of said side components and bridging said center sill.

10. Cross ridge and brace construction for a hopper car or the like according to claim 8, wherein the cross bearer is of composite construction with complementary vertical web side components secured at their inner ends to the opposite sides of the center sill, and a ridge sheet supporting flange member secured along the upper edges of said side components and bridging over said center sill.

11. Cross ridge and brace construction for a hopper car or the like according to claim 8, 15 wherein the cross bearer is of composite construction with complementary vertical web side components secured at their inner ends to the opposite side of the center sill, a compression chord member secured along the upper edges of 20 said side components and bridging said center sill, and a tie plate constituting a tension chord which extends beneath the center sill from one side sill to the other and which is secured to said

center and side sills as well as to the bottom edges of the side components of the cross bearer.

12. Cross ridge and brace construction for a hopper car or the like with a center sill, side sills and side wall sheet-supporting stakes up-standing from the side sills, comprising a cross bearer which extends transversely of the center sill and to the ends of which the side sills are secured, a continuous ridge sheet overlying the center sill and the cross bearer, and side wall brace means including a pair of complementary-inclined brace bars whereof the upper ends are secured to corresponding side wall stakes and which extend down through openings in the ridge sheet for attachment of their lower ends to the cross bearer adjacent the center sill. 10

13. Cross ridge and brace construction for hopper cars and the like according to claim 1, wherein the opening through which the brace means passes is sealed by welding. 15
